UNITED STATES PATENT OFFICE

WILLIAM H. HOODLESS, OF PHILADELPHIA, PENNSYLVANIA

CRUSHER FOR RAW SUGAR IN BAGS

Application filed December 5, 1927. Serial No. 237,966.

The present device is intended to crush raw sugar that has solidified in bags. It operates as the bags containing the raw sugar are in transportation to the bins. The raw sugar coming to the refineries situated along the seaboard or otherwise in places inaccessible to water transportation from the tropics, is shipped in bags containing 250 lbs. and upward of raw sugar each, discharged and weighed and usually also sampled while in the bags and, by modern practice conveyed by a belt conveyor to a place of discharge where the bags are held mouth downward over a chute leading to raw sugar bins. These bags frequently arrive at the port of discharge with the raw sugar so solidified by freezing or other cause, that the sugar will not flow out from them when held mouth downward over the chute.

20 The present device crushes the solidified sugar while in the bags, as it is carried by the belt, sufficiently to cause it to flow readily from the inverted bag, without injuring most of the bags passing through the device.

25 Fig. 1 is a plan view of the device and a portion of the belt that carries the bags. Fig. 2 is an elevation of the device the belt appearing in cross-section. Fig. 3 is an elevation showing the device looking from the side toward the belt. Fig. 4 is a view of the standard and carriage with the end plate and screw removed.

30 The two crusher rollers 1, 1, are positively driven at a rate that causes their circumferences to travel at substantially the speed of the belt or a trifle faster preferably so as to avoid crowding the sugar toward the end of the bag. They are mounted in bearings 2, that are adjustable toward and away from the belt, and have means for securing them in positions suitable for crushing the solidified sugar, and they are placed opposite each other so that the sugar will be crushed between them. The circumferential surface of 35 the crusher rollers may be smooth, or may be slightly roughened to enable it to take hold of the bags, but must not be such as will cut or tear the bags as these are used repeatedly.

50 The best embodiment of my device of

which I am at present aware I will now describe:—I place at the sides of the belt 4 a pair of standards, 5, each carrying a track, 7, in which travels the carriage 8, that has bearings, 2, for the shaft, 9, of the roller, 1. The 55 standard, 5, is provided with means such as the screw, 12, for moving the carriage, 8, along the track, 7. The shaft, 9, has a sprocket pulley, 10, which is driven by the chain, 11, that is driven at a speed that will cause the circumference of the crusher rollers to travel at a speed substantially equal to the speed of the travel of the belt. Preferably this chain is driven directly or indirectly from the belt driving mechanism.

60 The chain 11, may extend very conveniently to the sprocket drive pulley, 20, that is mounted on the drive shaft, 21, that also carries a bevel gear, 24, meshing with a bevel gear, 25, on the shaft, 26, carrying the drum, 28, over which the belt, 4, passes. This shaft is driven by an electric motor, 22, and the relative diameters of the drive pulley, 26, and the driven sprocket pulley, 10, and the crushers, 11, will be such that the circumferential speed of the crushers will be equal to the rate of the travel of the belt, 4.

65 The bags are always somewhat flattened when they arrive at the refinery, and lie on the belt lengthwise, and with a flattened side upon the belt. The pressure exerted upon them by the crusher rollers, 1, will not burst the bag unless the sugar is crowded toward one end of the bag. This crowding is avoided by making the crusher rollers, 1, travel as fast as or preferably a little faster than the speed of the belt, or by roughening slightly the circumference of the rollers. The crushing need not be deep. If the sugar is not too hard the driving mechanism on one roller may be dispensed with and it may be made to rotate by the rotation of the other roller transmitted through the bag.

70 A number of changes in the mechanism can be made without departing from my invention the essentials of which are the use of the crushing rollers placed on the opposite sides of the belt, and opposite each other and being adjustable toward and away from each other and being positively driven at a 75

speed equaling or exceeding in a small degree the belt speed, and having a circumferential surface that will not cut or tear the sugar bags.

5 I claim—

1. In combination with a conveyor for bags of raw sugar, of the belt conveyor type, a pair of crusher rollers placed opposite each other at the sides of the belt, and having their axes of revolution vertical, positive driving mechanism driving the same at a circumferential speed substantially equal to the speed of travel of the belt, bearings in which said rollers are rotatively mounted, and mechanism for varying and fixing the distance between said rollers.
- 10 2. The device as defined in claim 1 with the following additional limitation; the circumferential surface of the rollers being roughened sufficiently to enable them to grasp the bags, but without sharp edges and without grooves sufficiently deep to cause the rollers to tear the bags.
